UNITED STATES PATENT OFFICE.

ARTHUR F. H. HEAD, OF PHILADELPHIA, PENNSYLVANIA, ASSIGNOR TO THE J. G. BRILL CO., OF PHILADELPHIA, PENNSYLVANIA, A CORPORATION OF PENNSYLVANIA.

CAR-TRUCK.

1,107,301.

Specification of Letters Patent. Patented Aug. 18, 1914.

Application filed September 23, 1913. Serial No. 791,278.

To all whom it may concern:

Be it known that I, ARTHUR F. H. HEAD, a subject of the King of Great Britain, and resident of Philadelphia, in the county of Philadelphia and State of Pennsylvania, and whose post-office address is care of The J. G. Brill Co., Sixty-second street and Woodland avenue, in said city, have invented certain new and useful Improvements in 10 Car-Trucks, of which the following is a specification.

My invention relates to improvements in swing bolster car trucks, and particularly to that class wherein semi-elliptical or leaf 15 springs or other equivalent form of bolster supports are carried from the side frames of the truck by swinging links or hangers, and in which the bolster is supported on said leaf springs, etc., by other springs.

20 My present invention consists in certain details of construction and combination of parts hereinafter described, and finally pointed out in the claims.

In the drawing, forming part of this 25 specification, Figure 1 is a side elevation showing a portion of the side frame of a car truck and the improved construction supported therefrom; Fig. 2 is an enlarged elevation of a fragment of the truck, partly in 30 section, on the line 2—2 of Fig. 1; and Fig. 3 is a like view partly in section on the line 3—3 of Fig. 2.

Similar reference characters designate like parts throughout the several views.

35 For the purpose of describing my invention, I have not deemed it necessary to illustrate an entire truck construction, as those skilled in the art are familiar therewith. However, for the purpose of further illustration, reference is made to the truck shown 40 in the application filed by Walter S. Adams, on the 18th day of June, 1913, Ser. No. 774,286, Patent No. 1,076,009, dated October 14, 1913.

45 In the drawing, 1 is an intermediate portion of the side bar or upper chord of the car truck frame. This is usually provided with pedestals of conventional or desired construction. It will be understood that all 50 of the parts hereinafter described, except the bolster and spring plank are duplicated at each side of the truck, the pedestals engaging axle boxes, which hold axles and wheels in the usual manner. The side bars 55 or upper chords are connected transversely

by the usual transoms 2 shown in dotted lines in Fig. 1, and other crossings in the usual manner.

At 3 are hangers comprising the side bars 4, 5, which are slightly splayed outwardly, 60 lower sections 6, 7, provided with upturned ends 8, 9, and upper curved portions 10. The hangers 3 embrace the side bar 1 and the curved portion 10 rests on bearings 11 which allow the hangers to swing transversely of the truck. The ends 8 and 9 of the hangers support blocks or spring seats 12. At 13 is a semi-elliptic leaf spring, which, in the present case, is arched upwardly, its ends being provided with projections 14 engaging the spring seats 12. As above stated, it will be understood that there are two of such springs, one on each side of the truck and disposed longitudinally below the plane of the side bars. At 15 is 75 the spring plank, consisting of a channel bar having a lower horizontal web 16 and upright flanges 17, the upright flanges being gradually reduced in height, in order to clear the side bar, as shown at 18, in Fig. 2. 80 The semi-elliptic spring 13 is provided with the usual form of strap 19 and at 20 is a block provided with a recess, in which the strap is seated, and at 21 is a like block, in which the upper portion of the strap 18 is 85 seated, the horizontal web 16 of the spring plank resting on the block 21. Bolts 22 pass through the plates 20, 21, and the lower web of the spring plank and secure them firmly together. In this manner, the leaf springs 90 and hangers on both sides of the truck are connected transversely.

At 23 is the bolster, which consists of a channel beam having a horizontally disposed web 24 and pendant side flanges 25, the beam being wider than the spring plank and inverted, so that its side flanges depend about and embrace the side flanges 17 of the spring plank, sufficient clearance being allowed between the respective flanges for a 100 working fit. The side flanges 25 are also preferably reduced in diameter at their ends, as at 26, the ends of the top web 24 preferably terminating a short distance within the side bars and adjacent the end of the reduced portions 18 of the spring plank. At 27 is a casting resting on the web 24 of the bolster, and which in turn supports the side bearings or rub plates 28. At 29 are spring seats secured by a bolt 30 to the lower web 110

16 of the spring plank and at 31 is a spring seat secured to the web 24 of the bolster, a bolt 32 passing through the casting 27, web 24 and spring seat 31, securing those parts 5 together. Between the spring seats 29 and 31 extends a spiral spring 33. A compact structure is thus produced and in addition, the bolster is supported on the longitudinally disposed leaf spring by further springs 10 disposed within the plane of the side bars and the leaf springs. The leaf spring and spiral spring have different rhythmic movements and tend to more perfectly support the car body while the hangers allow a limited amount of transverse swing.

Within the scope of the appended claims, my invention may be variously embodied without departing from its spirit.

Having described my invention, I claim:

20 1. In a car truck, the combination with the side bars of the truck frame, longitudinally disposed semi-elliptic springs movably hung from the side bars, a spring plank transversely connecting the leaf springs, the 25 said connection and suspension enabling the springs and plank to swing bodily transversely of the truck, springs on the spring plank, a bolster on said springs, and transoms connecting the said bars between which 30 the said bolster lies.

2. In a car truck, the combination with the side bars of the truck frame, leaf springs movably supported on the side bars, a spring plank connecting the said leaf springs, up-

wardly extending spiral springs on the 35 spring plank, a bolster on said spiral springs, and transoms extending between the said bars and between which the said bolster lies.

3. In a car truck, the combination with 40 the side bars of the truck frame, longitudinally disposed leaf springs, swing hangers supporting the leaf springs from the side bars, transoms connecting the side bars, a spring plank secured to the leaf springs, 45 springs on the spring plank within and adjacent the side bars, a bolster located between the transoms and having its ends extending adjacent the side bars and resting on the said latter springs.

4. In a car truck, the combination with 50 the side bars of the truck frame, longitudinally disposed leaf springs supported on the side bars, a spring plank comprising a U-shaped channel bar, transoms extending between the said bars, a bolster comprising an inverted channel beam embracing the spring plank, spring seats within the channels of the spring plank and bolster and springs extending between said spring seats.

Signed at the city and county of Philadelphia, State of Pennsylvania, this 16th day of August, 1913.

ARTHUR F. H. HEAD.
